UNITED STATES PATENT OFFICE.

EVERETT W. SWARTWOUT, OF WHITE PLAINS, NEW YORK.

UNIFLOW-ENGINE SYSTEM.

1,333,139.

Specification of Letters Patent.

Patented Mar. 9, 1920.

Application filed June 22, 1916. Serial No. 105,114.

To all whom it may concern:

Be it known that I, EVERETT W. SWARTWOUT, a citizen of the United States of America, residing at White Plains, Westchester county, State of New York, have invented certain new and useful Improvements in Uniflow-Engine Systems, of which the following is a specification.

This invention relates to uniflow engine systems.

More particularly, my invention relates to a motive power system comprising high and low pressure units, one or both of said units comprising a uniflow engine. In certain preferred forms of my invention, a superheater is employed, the same being disposed posterior of a high pressure unit and anterior of a low pressure unit.

I have discovered that a power plant system comprising one or more uniflow engines arranged as a high pressure or a low pressure unit, or both, operates to essentially increase the efficiency and total power output of the system, to materially decrease the consumption of steam per unit horse power developed per hour and further to enlarge the flexibility of operation of the system by increasing the range of speeds as well as the total power outputs of the several units when driving independent shafts and by equalizing the thrust of the pistons of the several units. By virtue of the uniflow engine arranged in my system as herein described, means are provided for superheating the whole or a part at will of the exhaust steam of the high pressure unit prior to entry into the intake of the low pressure uniflow engine unit, whereby condensation of steam or other similar medium is obviated and moisture within the exhausted medium is precluded. In such forms of my invention in which the superheater is employed, such superheater is preferably heated by the hot flue gases of the boiler supplying the steam to the high pressure unit, whereby the energy made available through the superheated and saturated steam to the low pressure unit is in a most advantageous form.

The most preferred form of my present invention comprises a uniflow engine having the construction described and claimed in my pending application Serial No. 101,511, in accordance with which each head of the uniflow cylinder is provided with means for

automatically regulating the clearance of the cylinder.

Further features and objects of my invention will be more fully understood from the following description and the accompanying drawings, in which—

Figure 1 diagrammatically shows one form of my invention; and

Figs. 2, 3, and 4 show diagrammatically other forms of my invention.

Referring to Fig. 1, the boiler 1 is connected by the piping 2 with the inlets 3 of the uniflow engine 4. The uniflow engine 4 may be of any type. The exhaust 5 of engine 4 is connected by the piping 6 to the receiver 7 and thence connected by the piping 8 with the inlets 9 of the uniflow engine 10. The exhaust 11 of engine 10 is connected through 12 with the condenser 13.

The connection of the piping for heating purposes or other desired supplementary uses is indicated at 14, and is preferably connected with the exhaust 11 of the uniflow engine 10 as by connecting said piping 14 with the exhaust piping 12.

In the aforesaid construction, the first unit comprising one or more uniflow engines operates on the high pressure steam supplied by the boiler and the second unit comprising one or more uniflow engines is driven by the lower pressure steam furnished from the exhaust of the first unit. Such arrangement is rendered highly efficient by the employment of the receiver 7 into which the exhaust of the first unit is discharged. The capacity of the receiver 7 will be determined by the capacities of the first unit and the second unit and to provide for the proper accumulation of the steam exhausted from the first unit to effect the desired efficiency of operation of the second unit.

Referring to Fig. 2, the boiler 20 is connected through the piping 21 with the high pressure unit shown as a uniflow engine 22. The exhaust of said engine 22 is connected by the piping 23 with the receiver 24 of the character set forth above. The receiver 24 is connected by the piping 25 with the superheater 26, shown as fired jointly with the boiler 20. After superheating the steam is conveyed from the superheater 26 through the piping 27 to the inlet ports 28 of the uniflow engine 29, which exhaust through the pipe 30 into the condenser 31.

The piping for heating or other auxiliary purposes is connected in suitable relation to the exhaust of the uniflow engine, as by connecting such auxiliary piping 32 to the pipe 30.

Under certain circumstances, the piping 33 is preferably cross-connected between the piping 21 and the piping 25, and provided with the valve 34 to control the extent of flow of the live steam from the high pressure piping 21 to the low pressure piping 25, whereby the whole or part of the exhaust steam of the high pressure unit is superheated and admixed in desired proportion with steam supplied directly from the steam supply.

The piping for heating or other purposes may also be connected to the reservoir 24 as indicated by the piping 35.

Similarly, as shown in Fig. 3, of my invention, the high pressure line 40, supplied by boiler 41, is connected to the inlet ports 42 of the uniflow engine 43 and the exhaust steam therefrom conducted to the receiver 44, thence to the low pressure unit, shown as the turbine 45, to the exhaust of which is connected the piping 46 of the heating system or other auxiliary piping. The exhaust of the low pressure unit 45 may be connected with the condenser 47, if desired.

In the arrangements shown in Figs. 1 and 3, the steam heating system may be connected with the receiver by piping 70, such heating system being independent of or in conjunction with the heating system supplied otherwise in the aforesaid arrangements. Also in said arrangements, the piping 69 may be connected to the high pressure line and provided with the pressure reducing valve 71 and stop valve 72 to control the pressure and flow to the low pressure unit.

In Fig. 4 I have indicated the superheater 50 supplemented with live steam by means of cross-piping 51 communicating with the high pressure line 40, thence leading from the superheater 50 to the low pressure unit, shown as the turbine 45, and the heating system 46 connected with the exhaust of the turbine 45 similar to the arrangement shown in Fig. 2. Also, similar to Fig. 2, the heating system 52 may be connected with the receiver 53, either separate from or in conjunction with the heating system 46 connected with the exhaust of the low pressure unit 45. The cross piping 51, in Fig. 4, is similarly arranged as in Fig. 2, and comprises the provision of the valve 55 to control the amount of live steam transmitted from the high pressure line 45 to the intake piping 56 of the superheater 50. The outflow piping 57 of the superheater 50 is connected to the low pressure unit shown as the turbine 45.

The advantages of the superheater interposed between the primary and secondary

units results in materially increasing the effective total work done by the high pressure and low pressure units, both severally and jointly, as will be clearly shown by the entropy diagrams corresponding to the respective several forms of my invention. Such favorable results are particularly attained when the means for supplying steam from the system for heating or supplementary or other purposes is connected to the system in the manner indicated herein.

In Figs. 2 and 4 the valves 34 and 55 may be valves of the pressure reducing type, in which case the stop-valves 60 are also employed.

The valves 61 in the several forms of my invention are throttle valves in the piping leading to the high pressure unit and valves 66 are stop valves in the exhaust thereof.

As indicated in Figs. 2 and 4, the superheater may be cut off by closing the stop valves 62 in the intake piping of the superheater, in which case the low pressure unit will be operated by utilizing the saturated steam through piping 63 from the exhaust of the high pressure unit, similar to Figs. 1 and 3, supplemented if desired with live steam from the high pressure piping as controlled in pressure and quantity by the respective valves 55, 60. The piping 63 is provided with the stop valve 64 at the indicated location.

The outflow piping of the superheater in Figs. 2 and 4, is provided with the stop valves 65 located between the superheater 100 and the T connection with the piping 63.

Also, in the arrangement of Fig. 2, the low pressure unit 29 may be a four valve steam engine, while the high pressure unit is of the uniflow type.

In each of the aforesaid arrangements, where a plurality of high pressure units is employed, the same may be connected in parallel to each other with the high pressure line and exhausting to a common receiver, or the same may be connected in series, i. e., multiple expansion relation. Thus, generally, if more than one unit is employed to replace the high pressure unit, any one may vary in capacity from any other or all 115 and these units may be connected in parallel or in series, or both, as determined by the results desired to be attained.

Similarly, with respect to the low pressure unit, when employing a plurality of 120 devices the same may be connected in series or in parallel, or both, and may be varied in capacity as desired.

In the several forms of my invention as herein described, the respective high pressure and low pressure units constitute prime mover units to actuate one or more driven shafts to which the said units are connected, either directly or indirectly as will be understood by the art.

In the arrangements shown in Figs. 1 and 3, the steam heating system may be connected with the receiver by piping 70, such heating system being independent of or in conjunction with the heating system. Also, in said arrangements, the piping 69 may be connected to the high pressure line, and provided with the pressure reducing valve 71 and stop valve 72 to control the pressure and flow to the low pressure unit.

I have also shown the aforesaid system advantageously adapted for supplying steam for manufacturing purposes. For such purposes, the steam is usually required at a predetermined range of temperature, condition of saturation and oftentimes at a predetermined range of pressure. A highly practical form of such embodiment of my invention is shown in Figs. 2 and 4, in which the steam piping for manufacturing purposes is connected at 75, and the pressure controlled by the pressure valve 76. The valve 77 is a stop valve. In such form, the steam utilized is the saturated steam discharged through the exhaust of the high pressure or first unit and preferably subsequently superheated to the desired temperature by the superheater 26, of Fig. 2, or superheater 50, of Fig. 4. The pressure of the steam in the outflow piping 27 (see Fig. 2) or piping 57 (Fig. 4), conditioned on the initial pressure of the high pressure piping of the boiler, the drop in pressure at the exhaust of the high pressure unit, the pressure factors of the receiver, superheater and the auxiliary pressure valves 55, together with the drops in pressure in the several pipings, etc. as understood by the art, is eventually determined by the pressure valve 76, in accordance with the particular conditions of the manufacturing desired to be effected.

In the above arrangements, the initial supply of steam and intermediate stage, preferably supplemented by superheating, are arranged relative to the heating, or manufacturing or other auxiliary piping to secure the maximum efficiency of the high and lower pressure units. Also, my invention affords a balancing effect between the high pressure unit, on the one hand, and the low pressure unit, on the other hand, relative to withdrawal of steam through the heating or manufactory portion of the system.

The temperatures of the high pressure portions may be raised to relatively high pressures, as for example say 570° F. and the saturated or exhaust steam in such case may be superheated, say to from 550° F. to 600° F. The operation of my invention will be understood largely from the foregoing, together with the following.

Referring to Figs. 1 and 3, the initial steam supply is furnished to the high pressure unit or units, which exhaust into the re-

ceiver, and conveyed thence to the low pressure unit or units. With the conjoint employment of the cross-piping 69, Fig. 1, the desired amount and pressure controlled respectively by the valves 72, 71, is supplied directly from the initial steam line 2 to the receiver 7. Or, as in Fig. 3, the live steam is directed by the cross-piping 69 from the initial pressure line 40 conjointly with the steam flowing from the receiver 44 into the low pressure unit 45. In said Figs. 1 and 3, upon withdrawing steam through withdrawing means 70 for heating, or manufacturing or other purposes, the system will be balanced by the steam of proper pressure and quantity flowing through said cross piping 69. Such balancing effect results in maintaining substantially uniform pressure of the steam of the intakes of the high and low pressure units and as uniform condition of the steam at the respective inlets as practicable but whatever variation does take place, is distributed substantially uniformly. Similarly, upon withdrawing steam through the withdrawing means 14 of Fig. 1, or withdrawing means 46 of Fig. 3, the balance of the receiver systems will be maintained. Again, in the arrangement of Fig. 2, the steam under desired pressure and of desired quantity transmitted through the cross-piping 33 and through the superheater 26 maintains the balance of the steam irrespective of the amount of steam withdrawn through either or any or all of the withdrawn means indicated at 32, 35, 75. Similar to Fig. 2, the arrangement shown in Fig. 4 is maintained in balanced relation by means of the cross piping 51 controlled by the stop valve 55 and the pressure valve 60.

In the several forms of my system embodying means for withdrawing steam from one or more points of the system, the system is balanced at the several points of utilization of the medium whereby the medium is supplied at the desired temperature and pressure to the respective high pressure and low pressure units while at the same time the medium is withdrawn for industrial and other auxiliary purposes at the said one or more points at the desired pressure and temperature, or at the desired condition of steam.

In the arrangements of Figs. 1 and 3, upon cutting out the high pressure unit by shutting off the respective valve 61, the low pressure unit indicated as 10, 45, in the respective figures, will be operated by the use of the cross piping 69, controlled in pressure by the valve 71 and in quantity by the stop valve 72. In the arrangements of Figs. 2 and 4, the high pressure unit may be cut out by shutting off the stop valve 61, and valves 66, also if desired, and transmitting the steam to the low pressure unit, indicated 29 in Fig. 2 and 45 in Fig. 4, through the

piping 63; under such conditions, the superheater 26 may also be employed in conjunction therewith through the piping 25 and the low pressure, superheated line 27.

5. It will accordingly be seen that I have provided a substantially universally flexible system comprising the high pressure and low pressure units operated as set forth hereinabove.

10 By reason of the combination of a uniflow device, *i. e.*, a device comprising a piston, a cylinder provided with a plurality of inlet openings and inclosing said piston, and further provided with one or more central exhaust ports controlled by said piston, as a high pressure unit or as a low pressure unit, or both, as herein described, there is attained increased efficiency under wide limits of load, material decrease in fuel consumption 15 per output of driving energy and an unusual extent of flexibility in increased driving speed combined with increased torque without causing abnormal strains on any part of the system.

20 25 The invention is particularly adapted for use on self-propelled vehicles, motor boats and motor ships in that the aforesaid advantages of the system may be more effectually utilized in such uses, although, it will 30 be understood that the invention may be advantageously embodied in stationary systems.

35 By the expression "balancing" as employed herein, I include the result attained by my invention of effecting like proportional increase in the pressure of the steam transmitted to the respective high pressure and low pressure units under the condition of decrease of the volume or pressure, or 40 both, of the steam led from the system for heating or other general use, and, also, vice versa, like proportional decrease in the pressure of the steam transmitted to the high pressure and low pressure units respectively 45 upon increase in volume or pressure, or both, of the steam employed for heating or other industrial purposes.

50 Whereas I have described my invention by reference to specific forms thereof, it will be understood that many changes and modifications may be made without departing from the spirit of my invention.

I claim.

55 1. A system comprising in combination with a supply of steam, a high pressure unit, a low pressure uniflow engine unit, a superheater connected to the exhaust of said high pressure unit, passage means connecting said supply directly with said superheater, means for withdrawing steam for auxiliary purposes, disposed anterior of said low pressure unit.

60 65 2. A system comprising in combination with a supply of steam, a high pressure unit, a low pressure unit, a superheater connected

to the exhaust of said high pressure unit, passage means connecting said supply directly with said superheater, and means for withdrawing steam for auxiliary purposes, said means being connected posterior of said 70 superheater.

3. A system comprising in combination with a supply of steam, a high pressure unit supplied directly by said steam supply, a superheater connected posterior of the exhaust of said high pressure unit, passage means connecting said supply directly with said superheater and a low pressure unit connected posterior of the outlet of said 75 superheater.

4. A system comprising in combination with a supply of steam, a high pressure unit supplied directly by said steam supply, a superheater disposed posterior of said high pressure unit, a low pressure unit, passage 80 means connecting said supply directly with said superheater, disposed posterior of the outlet of said superheater and means for supplying steam directly from said steam supply to the intake of said low pressure 90 unit.

5. A system comprising in combination with a supply of steam, a high pressure unit supplied directly by said steam supply, a superheater disposed posterior of the exhaust of said high pressure unit, a low pressure uniflow engine unit, passage means connecting said supply with said superheater disposed posterior of the outlet of said superheater, means for withdrawing steam for 100 auxiliary purposes disposed posterior of the outlet of said superheater and means for supplying steam directly from said steam supply to said low pressure uniflow engine unit and said steam withdrawing means. 105

6. A system comprising in combination with a supply of steam, a high pressure unit, a low pressure uniflow engine unit, and means for re-heating the whole or a part at will of the exhaust steam of said high 110 pressure unit prior to entry into the intake of said low pressure uniflow engine unit.

7. A system comprising in combination with a supply of steam, a high pressure unit, connected directly with said steam supply, 115 a low pressure uniflow unit, a superheater disposed posterior of said high pressure unit and anterior of said low pressure unit and means connecting said supply directly with said superheater.

8. A system comprising in combination with a supply of steam, a high pressure unit, a low pressure uniflow engine unit, a superheater disposed anterior of said low pressure unit, means connecting said supply directly with said superheater and piping for auxiliary purposes connected to the outtake of said superheater. 125

9. A system comprising in combination with a supply of steam, a high pressure 130

uniflow engine unit, a low pressure uniflow engine unit, a superheater disposed anterior of said low pressure uniflow engine unit, piping for auxiliary purposes connected to 5 the outtake of said superheater, passage means connecting said supply directly with said superheater, and means for controlling the pressure in said piping.

10. A system comprising in combination with a supply of steam, a high pressure unit, a low pressure uniflow engine unit, and means for superheating the whole or a part at will of the exhaust steam of said high pressure unit prior to entry into the intake 15 of said low pressure uniflow engine unit.

11. A system comprising in combination with a supply of steam, a high pressure unit, a low pressure uniflow engine unit, means for superheating a desired proportion of 20 steam supplied directly from said steam supply admixed in whole or in part at will of the exhaust steam of said high pressure unit, and means for leading the superheated steam to the intake of said low pressure uniflow engine unit.

12. A system comprising in combination with a supply of steam, a high pressure uniflow engine unit, a low pressure uniflow engine unit, means for withdrawing steam for 30 auxiliary purposes, and means for balancing the system irrespective of the amount of withdrawal of steam through said withdrawing means, said balancing means comprising passage means connecting said supply directly with said low pressure uniflow engine unit.

13. A system comprising in combination with a supply of steam, a high pressure uniflow engine unit, a low pressure uniflow engine unit, a superheater disposed posterior of said high pressure unit, means for withdrawing steam for auxiliary purposes and means for balancing the system irrespective of the amount of steam withdrawn through 45 said withdrawing means, said balancing

means comprising passage means connecting said supply directly with said superheater.

14. A system comprising in combination with a supply of steam, a high pressure uniflow engine unit, a low pressure uniflow engine unit, a superheater, piping connecting the intake of said superheater with the exhaust of said high pressure unit and said steam supply, and means for withdrawing steam for auxiliary purposes. 50

15. A system comprising in combination with a supply of steam, a high pressure unit, a low pressure uniflow engine unit, and means for superheating the whole or a part at will of the exhaust steam of said high pressure unit prior to entry into the intake of said low pressure uniflow engine unit, said superheating means comprising passage means connected directly with said supply. 55

16. A system comprising in combination with a supply of steam, a high pressure uniflow engine unit, a low pressure uniflow engine unit, means for superheating a desired proportion of steam leading directly from 70 said steam supply admixed in whole or in part at will of the exhaust steam of said high pressure unit, said superheating means comprising a superheater and passage means connecting said supply directly 75 with said superheater.

17. A system comprising in combination with a supply of steam, a high pressure unit, a low pressure uniflow engine unit, means for re-heating a desired proportion of 80 steam supplied directly from said steam supply admixed in whole or in part at will of the exhaust steam of said high pressure unit and means for leading the re-heated steam to the intake of said low pressure uniflow engine unit. 85

In testimony whereof I have signed this specification.

EVERETT W. SWARTWOUT.
